COMBINED RETAINING AND DISPENSING CARD
FOR A COILED FISHING LINE

Leon L. Martuch, Midland, Mich., assignor to Scientific
Anglers, Inc., Midland, Mich.

Filed Mar. 30, 1972, Ser. No. 239,835

Term of patent 14 years

Int. Cl. D9—03
U.S. Cl. D9—171

FIG. 1

FIG. 2

FIG. 3

FIG. 4

FIG. 1 is a top plan view of a combined retaining and dispensing card for a coiled fishing line showing my new design;

FIG. 2 is a top perspective view in its folded configuration;

FIG. 3 is a top plan view in its folded configuration; and

FIG. 4 is a bottom plan view thereof.

The dash lines represent score lines.

I claim:

The ornamental design for a combined retaining and dispensing card for a coiled fishing line, substantially as shown and described.
